United States Patent Office.

DAVID W. BOWDOIN, OF SALEM, MASSACHUSETTS.

Letters Patent No. 105,300, dated July 12, 1870.

IMPROVEMENT IN ELASTIC TRANSFER PRINTING.

The Schedule referred to in these Letters Patent and making part of the same.

To all whom it may concern:

Be it known that I, DAVID W. BOWDOIN, of Salem, in the county of Essex and State of Massachusetts, have invented a new and useful Improvement in Elastic Transfer Printing; and I do hereby that the following is a full, clear, and exact description of the same.

The object of my invention is to produce a yielding transfer-surface, by means of which impressions may be taken of engravings, either in relief or intaglio, or of any composition in ordinary type, or other raised and depressed surfaces, and by which these impressions may be transferred to any other surface or object of regular or varying form or outline, with ease and facility, the lines of which represent with absolute fidelity the original from which it is made.

To accomplish this result I make use of an elastic composition of such density that the surface will yield to the impression made by the type just enough to reproduce the inked or sized surface, and accommodate itself to the rigidity of the type.

I make this transfer-surface either of vulcanized rubber, or the composition of glue and molasses, such as is used in making printers' rollers. This composition I prefer to use in most cases, as being best adapted to the purpose. This composition is well known, and I do not consider a detailed account of its manufacture necessary in this description.

The composition being melted, it is cast in plates of any desired thickness or size, the smooth surface being obtained by forming one or both sides of the mold of a sheet of plate-glass, by which a perfectly even and true surface is produced, the thickness being perfectly uniform. Any other material capable of producing an equally smooth surface may be used in place of the plate-glass. The plate of elastic material, being firmly cemented to a rigid backing or plate, is immediately ready for use.

The composition may be cast in the form of a roller, when it is desired to use it in a press requiring a surface of that form, or any form may be used which is required to produce any desired result.

For producing or transferring large surfaces, a curved

plate may be used; for irregular surfaces, the block must be cast so as to conform to their varying outlines.

I do not propose to describe any particular form of machine or press in which this surface may be used, as it is obvious that many such machines may be devised which will facilitate the operation of transferring and printing.

In making use of this transfer-surface, the engraving or type to be transferred is first to be inked or sized in the usual way, and pressed directly upon the elastic surface. If required, the impression thus obtained may be again transferred to another similar surface. The object to be printed is then rolled over or pressed upon the surface, or printed in any suitable manner by means of machines or presses which may be devised for this purpose.

Suitable sizing being used, the resulting impression may be ornamented by bronze or colored powders, in many ways well known to those skilled in the art.

I do not claim any composition of matter for this purpose, as I am aware that such combination of materials for making elastic compounds is the subject of various patents.

Having thus fully described the nature of my invention,

What I claim as new, and desire to secure by Letters Patent, is—

1. An elastic yielding transfer-surface or plate composed of the materials specified, or their equivalents, prepared as set forth, and used in the manner and for the purpose substantially as specified.
2. Forming a transfer-surface of an elastic yielding material, to be used for printing and decorating objects of regular or irregular outline.
3. The method of printing and transferring, by means of an elastic transfer-surface, substantially as set forth.

DAVID W. BOWDOIN.
